UNITED STATES PATENT OFFICE.

GORDON C. CURRY, OF NORTH CANTON, OHIO, ASSIGNOR, BY MESNE ASSIGNMENTS, TO THE HOOVER COMPANY, OF NORTH CANTON, OHIO, A CORPORATION OF OHIO.

NOZZLE ADJUSTMENT FOR SUCTION SWEEPERS.

Application filed July 31, 1922. Serial No. 578,723.

This invention relates particularly to means for adjusting a nozzle of a suction-sweeper by raising and lowering the same with relation to the surface to be operated upon.

It is common practice in the manufacture of sweepers to provide at the front part of the machine a pair of axially-arranged supporting rollers or wheels adjacent the nozzle and to provide one or more supporting wheels positioned toward the rear of the machine. To raise or lower the nozzle with relation to the carpet or object to be cleaned, means are provided to raise or lower the axis of either the front or rear wheels.

An object of this invention is to provide means, of improved construction, for adjusting the axis of one of the supports of the device and which shall be positive in its operation and simple in its construction.

Other objects are to make the adjusting device quickly and easily operable to secure the desired adjustment, and to so construct the same that it will be very securely held in adjusted position to maintain the nozzle in any position given it with relation to the surface to be cleaned.

The above and other objects will become apparent from the following description taken in connection with the accompanying drawing, in the different figures of which the same reference numerals indicate like parts.

In the drawings:

Figure 1 is a side elevation of a suction-sweeper showing the application of my invention;

Figure 2 is a detail view showing the supporting bracket for the adjusting mechanism; and

Figure 3 is an enlarged sectional view through the adjusting mechanism, parts being shown in elevation.

Fig. 4 is a bottom plan view of the sweeper with minor details omitted.

Fig. 5 is a detail section of the spring ball retainer latch.

Designating the parts by reference characters, 10 indicates the motor-housing, 11 the fan chamber, 12 the intake-nozzle, 13 the discharge-spout. The above elements are essential parts of practically all suction-sweepers manufactured. The fan-chamber 11, intake-nozzle 12, and discharge-spout 13 are usually cast as an integral unit or so

connected together as to form a rigid frame which is supported adjacent the intake-nozzle by axially-separated wheels 14 mounted on an axle member 15 suitably connected to the cleaner frame.

Rearwardly of the wheels 14 and preferably positioned to run between the paths of the wheels 14 are a pair of axially-separated wheels 16. To raise and lower the intake-nozzle with relation to the surface to be operated upon, means are provided for vertically adjusting the axis of the rear wheels 16.

My invention is concerned with novel mechanism for raising and lowering the rear portion of the frame of the cleaner and with means for securing the adjusting mechanism securely in adjusted position.

A particular structure for accomplishing the objects of my invention will now be described.

The rear portion of the frame of the cleaner is supported on wheels 16 which are secured beneath the discharge-spout 13 by means of a bracket 17 which is secured to the underside of the discharge-spout by screws 18. The lower end of bracket 17 carries a pivot 19 on which is mounted link 20 carrying at the other end thereof an axle 21 on which the rear wheels 16 are journaled. Mounted on one end of axle 21 is the adjusting member 22. A double screw-thread 23 is cut on the intermediate portion of member 22 and the upper end is reduced as at 24 for a purpose to be more fully described later.

To provide an abutment for nut 25 to work against a bracket 26 is provided which is secured to flange 27 of discharge-spout 13 by means of screws 28. Bracket 26 is provided with two side-arms 29 and 30 near the outer ends of which are provided holes 31 and 32 for the reception of pivot pins 33 and 34.

Pivoted on pins 33 and 34 between the arms 29 and 30 is an annular ring 35 having a central opening 36 therethrough. On the upper side of ring 35 is provided a number of spaced depressions 37 the purpose of which will be more fully explained later. The necessity for mounting ring 35 on trunnions is due to the fact that as adjustment of the rear-wheels is made by screwing nut 25 up or down on threaded portion 23 of the adjusting member 22, this member takes different angular relations with respect to the

bracket because of its being mounted so that its lower end has movement through an arc of a circle.

Adjusting nut 25, by means of which adjustment of the rear wheel is caused by rotation on thread 23, of adjusting member 22 works against annular ring 35 as an abutment, and is provided at its lower end with a spring-ball retaining means for retaining the nut in adjusted position relative to the annular ring. This spring-ball retaining means comprises a ball 38 inserted in a hole 39 in the lower end of nut 25; between the ball and the inner end of hole 39 is placed a small spring 40 which tends to force the ball outwardly and into engaging contact with depressions 37 of the annular ring 35.

To prevent the nut 25 from being removed from adjusting member 22 under ordinary conditions of use its upper end is slightly counterbored as at 41 to form an abutment. In the upper end of the adjusting member 22 in the reduced portion 24 just above the screw-threaded portion 23 is provided a hole 42 in which pin 43 is inserted.

In order that nut 25 may be held from longitudinal movement so that the adjusting member 22 may be moved longitudinally therethrough on rotation of the nut, a lower reduced portion of the nut, as at 44, extends through hole 36 in annular ring 35 and this reduced portion is provided with a groove 45. Through the ring 35 is provided a hole 46 in which pin 47 may be inserted to engage groove 45.

In order that the adjustment of the nozzle may be readily ascertained, a pointer member 48 having an indicating point 49 is secured to adjusting member 22 at a point just below the threaded portion thereof by means of a pin 50 passing therethrough. On side member 30 of bracket 26 is provided a scale arranged so that divisions thereof indicate different heights of nozzle adjustment. The indicating point 49 of the pointer 48 co-operates with this scale in such manner that the particular nozzle adjustment at any time may be readily ascertained.

From a consideration of the structure above described, it is readily seen that a structure is provided wherein by means of a simple construction provision is made whereby the position of the nozzle may be readily adjusted.

When the rear wheel 16 is raised to its highest point of adjustment, if means are not provided to prevent it, the pin 43 may be run up above the top of the nut and exposed in such manner that it may be readily removed. To prevent this the upper end of the nut 25 is provided with a relatively large and shallow counterbore 51 in which a washer 52 is fitted, this washer being of

such size as to have a forced fit in the counterbore 51. Washer 52 is provided with a central hole through which the upper end 24 of the adjusting member 22 extends, but of such size that the pin 43 may not pass therethrough. Thus we have a construction wherein the upper end of the adjusting member 22 passes through the central opening of washer 52 which is of such a size that the pin 43 may not pass therethrough, providing a construction wherein the upper movement of the adjusting member 22 is limited by pin 43 striking washer 52.

It will be seen that I have provided a very simple, yet easily operable means, whereby the nozzle of a suction sweeper may be adjusted by an adjustment of the rear wheels thereof, and one wherein when the adjustment is made, is locked in such adjusted position.

I claim:

1. Nozzle adjusting means for a suction-sweeper comprising a rear wheel, an axle therefor pivotally connected with relation to the sweeper and an adjusting member attached to the axle, in combination with a bracket, a ring trunnioned thereon, a nut co-operating with the adjusting member for adjustment of the rear-wheel, mounted on the ring for rotation, and means on the nut and ring co-operating to retain the nut in a given relation to the ring.

2. A suction-sweeper comprising a fan chamber, a nozzle, and a discharge spout, in combination with front supporting wheels adjacent the nozzle and about the axis of which the nozzle may be fulcrumed, and rear wheels adjustably mounted so that the rear of the sweeper structure may be raised or lowered, the mounting comprising a bracket secured to the rear and on the under side of the sweeper, to the lower end of which are pivoted links which carry an axle on which the rear wheels are mounted, adjusting means comprising an adjusting member pivoted to the rear axle and having a screw-threaded portion, there being provided a nut fixed as regards longitudinal movement relative to the sweeper but which is adapted on rotation thereof to cause longitudinal movement of the adjusting member.

3. Nozzle adjustment means for a suction-sweeper comprising a bracket mounted under and to the rear of the sweeper, a pair of carrier wheels pivotally mounted on said bracket and an adjusting member having a screw-threaded portion, pivotally mounted on the axis of said carrier wheels, in combination with a member trunnioned on the sweeper and having mounted thereon a nut adapted for rotation but restrained from longitudinal movement relative thereto for co-operation with the threaded portion of the adjusting member and provided with a

spring-pressed latch means, the trunnioned member having indentations in a face thereof adapted to be engaged by latch means carried by the nut, the nut being provided with means for limiting the movement of the adjusting member in one direction, said means comprising a counterbore having a forced fit washer inserted therein, and means on the adjusting member to engage said washer. ¹⁰

Signed at Chicago, in the county of Cook, and State of Illinois, this 6th day of June, A. D. 1922.

GORDON C. CURRY.
